BY *Victor J. Evans*

UNITED STATES PATENT OFFICE

IVAN E. BEELER, OF PORTLAND, OREGON

DOOR LATCH

Application filed February 28, 1930. Serial No. 432,188.

This invention relates to certain new and useful improvements in latches for use upon doors opening to either side.

One of the principal objects of the invention resides in the provision and arrangement of foot operated means for actuating the latch.

An additional object of the invention consists of means for automatically resetting the latch upon releasing the foot operated means whereby the door will be retained in closed position when swung within the door frame.

With the above and other objects in view, the invention further consists of the following novel features and details of construction, to be hereinafter more fully described, illustrated in the accompanying drawings and pointed out in the appended claim.

In the drawings:—

20 Figure 1 is a fragmentary elevation of a door and frame thereof partly broken away to illustrate the construction and arrangement of the invention thereon for use in conjunction therewith.

25 Figure 2 is an enlarged longitudinal sectional view taken through the latch mechanism.

Figure 3 is a top plan view of the foot operated means.

30 Figure 4 is a fragmentary detail sectional view taken through that portion of the foot operated means having connection with the latch.

35 Figure 5 is a sectional view taken on line 5—5 of Figure 1.

Referring to the drawings in detail wherein like characters of reference denote corresponding parts, the reference character 10 indicates generally a conventional form of door frame

40 having a door, such as indicated at 11, swingably mounted laterally thereof upon pintles 12 and 13 bearingly mounted within blocks 14 on the upper surface of the floor and the under surface and rail of the uppermost or

45 top section of the door frame. All of the above is of the usual and well known construction incident to that of swinging doors and forms no part of the present application for Letters-Patent but the details of construction are mentioned merely for the purpose of

bringing about better understanding of the invention when associated therewith.

The latch construction, alluded to in the foregoing, embodies a housing 15 horizontally disposed within an appropriate portion of the door frame 10 and having its escutcheon plate 16 suitably arranged and preferably flush with the adjacent surface and side edge of the swingably mounted door 11. The latch bolt 17 slidably mounted within an apertured disk 18 anchored at a desired point in the length of the housing 15 carries an enlarged head 19 provided with oppositely inclined or beveled faces 20 upon the sides thereof and meeting at their outermost ends, as substantiated from the illustration of my invention in Figure 6 of the drawings.

The latch head 19 is also provided with shoulder portions 21 wholly within the housing 15 and designed for abutting engagement with the inner sides of an inturned flange 22 upon the outermost projecting end of said housing. When the shoulders 21 are forced against the flange 22, incident to the expanding action of a compression spring 23 encircling the latch pin 17 and sprung at its ends against the adjacent surfaces of the disk 18 and latch head 19, same will restrict further egress of the entire latch assembly. It is obviously apparent that the latch head 19 is engaged and disengaged with the stationary latch keeper escutcheon plate 16 in the ordinary manner.

A pulley wheel 24 horizontally disposed within one end of the housing 15 has trained thereover a connecting element or cord 25 joined at its uppermost end with the adjacent extremity of the latch bolt 17 and depending within the confines of the immediate hollow enclosure of the door frame for ultimate connection with a fulcrum lever 26 disposed beneath the floor surface. One end of the fulcrum lever is bifurcated, as at 27, to facilitate accommodation of an eye bolt or screw 28 and to project a common pivot pin 29 therethrough in order that the fulcrum lever may swing in a manner about to be described. A sleeve member 30, also projecting through the floor surface, is provided with attaching flanges 31 secured to the under surface of the

flooring, in the manner shown in Figure 4 of the drawings whereas guide flanges 32 depending as continuations of the walls of the sleeve 30 are projected upon opposite sides of the fulcrum lever 26 to prevent distortion thereof.

A cross bar 33, carried upon the opposite end of the fulcrum lever 26, carries foot engaging portions 34 upon the ends thereof having the heads projecting for given distances above the surface of the floor, as substantiated from the illustration of my invention in Figure 1. A retractile spring 35, encircling the connecting element 25 within the sleeve 30 is anchored at its ends to the latter and to that portions of the operating lever 26 disposed between the guide flanges 32.

From the foregoing description and accompanying drawings, it is understood that the springs 23 and 35 respectively will normally dispose the latch bolt in locking position and the fulcrum lever 26 as in Figure 1 whereby the door will be locked against entry by unauthorized persons but easily accessible to proper parties merely by the depressing of the foot engaging portions 35.

The invention is susceptible of various changes in its form, proportions and minor details of construction, and the right is herein reserved to make such changes as properly fall within the scope of the appended claim.

Having described the invention what is claimed is:

35 A latch comprising a housing, a spring pressed bolt slidably mounted in the housing, a lever pivotally mounted below the housing, a flexible element connecting said bolt with the lever, a sleeve slotted at its lower end and adapted to receive the lever, said flexible element passing through said sleeve and a spring housed within the sleeve and connected at one end with the sleeve and at its other end with the lever.

45 In testimony whereof I affix my signature.
IVAN E. BEELER.
